UNITED STATES PATENT OFFICE.

MAX ROBITSCHEK, OF VIENNA, AUSTRIA-HUNGARY, ASSIGNOR OF ONE-HALF TO LEO VON HERZ, OF SAME PLACE.

APPARATUS FOR VENTILATING AND COOLING STOKE-HOLES OF STEAMSHIPS.

SPECIFICATION forming part of Letters Patent No. 634,563, dated October 10, 1899.

Application filed March 23, 1899. Serial No. 710,258. (No model.)

To all whom it may concern:

Be it known that I, MAX ROBITSCHEK, a subject of the Emperor of Austria-Hungary, residing at Vienna, in the Province of Lower Austria and Empire of Austria-Hungary, have invented a new and useful Apparatus for Ventilating and Cooling the Stoke-Holes of Steamships, of which the following is a specification.

This invention relates to means for ventilating and cooling the stoke-holes of steamships, where temperatures of from 40° to 60° centigrade prevail. The attempts heretofore made for reducing such temperatures to a healthy degree have failed for the reason that they were based on mere ventilation, which gave rise to an unbearable draft of air.

According to this invention I cool and moisten the air used for ventilation, and to this end water-atomizers are so arranged in the upper parts of the usual ventilation-shafts as to produce a downwardly-directed jet of spray, which sucks in the air from without and at the same time cools and moistens it by its partial evaporation. The lower ends of the ventilation-shafts open into water-separators having inclined bottoms and baffle-plates, against which the current of air and spray impinges, and these separators communicate with chambers arranged in the ceiling of the stoke-hole and provided with a number of outlets for the cooled air, which descends in consequence of its greater weight. A pump driven by the engine or fed with steam from the boiler supplies the atomizers with the necessary water under pressure, and a filter is advantageously fitted to the suction-pipe of the pump.

In order to make my invention fully understood, I shall hereinafter describe the same in detail with reference to the annexed three sheets of drawings, in which—

Figure 1 is a sectional end elevation of the stoke-hole of a steamer provided with my improved ventilating apparatus. Fig. 2 is a sectional side elevation, on line 2 2, Fig. 3, of a ventilation-shaft having an atomizer arranged within its top portion and a water-separator connected with its bottom end.

Fig. 3 is a front elevation of the said ventilation-shaft, water-separator, and air-chamber; and Fig. 4 is a sectional top view, on

lines 4 4, Figs. 2 and 3, of the said parts. Fig. 5 is a front elevation, drawn to a larger scale and partly in section, of the atomizer used by preference; and Fig. 6 is a top view 55 of the said atomizer. Fig. 7 shows the nozzle of the atomizer. Figs. 8 and 9 are a sectional side elevation and top view, respectively, of the filter interposed into the section-piping of the pump feeding the atomizers. 60

Referring to Fig. 1 of the drawings, *a* is a steam-pump fed with steam by a neighboring boiler of the ship and sucking in water through the pipe *a'*, which opens into the stream or sea. Through the piping *a* the water under pressure delivered by the pump *a* is supplied to the atomizers *b*, arranged in the top portions of the ventilation-shafts *c*, which are of the ordinary well-known description. It is obvious that effective atomizers of any known construction may be used. The one shown by Figs. 5 to 7 is preferred as having given good results in practice. It consists of a globular body or water-receptacle *b'*, from which two or three radial elbow-pipes 70 *b*² are branched off. To the lower ends of the said elbow-pipes *b*² are screwed caps *b*³, having their bottom pierced by a number of inclined bores *b*⁴, the directions of which may be defined as those of tangents to helices. To 75 the said cap *b*³ screws a second cap *b*⁵, in which a hollow space or chamber *b*⁶ is formed having a central outlet-passage *b*⁷. The water under pressure entering the chamber *b*⁶ through the inclined bores *b*⁴ assumes within 80 the said chamber a rapid rotary movement, in consequence whereof the jet forced out through the passage *b*⁷ is atomized into a conical jet of spray. The downwardly-directed jets of spray having a certain velocity, they 85 suck in through the cowl *c'* of the ventilation-shaft *c* a certain quantity of air, and as by the atomizing of the water its vaporization is greatly facilitated a considerable portion of the spray passes to the state of vapor, 90 thereby absorbing heat which is abstracted from the ambient air. Consequently the air sucked in by the jets of spray is cooled and moistened. Besides that, it is thoroughly washed—that is to say, freed from dust. 95

In order to separate the currents of cooled, moistened, and washed air streaming down-

ward within the ventilation-shafts *c* from the particles of water they carry along, the said currents are caused to pass through the water-separators *d*. These water-separators are 5 sheet-metal receptacles provided with an inclined bottom *d'*, a baffle-plate *d²*, and an outlet *d³* at their lowest point, from which a discharge-pipe *d⁴* is run through the sides of the vessel. The water flowing downward along 10 the sides of the ventilation-shafts *c* is prevented from getting into the way of the current of air by a gutter *c²*, arranged along the inside of the lower edge of the shaft. It will be seen that the said gutter discharges the 15 water upon the highest portion of the inclined bottom *d'*, while the current of air flows toward the lowest portion, as indicated by the curved arrow in Fig. 2. By impinging against the baffle-plate *d²* the particles of water carried along are eliminated from the air and the retained water is allowed to pass downward through the hole *d⁵*, formed in the lower marginal portion of the plate *d²*. A further elimination of water takes place on the outer 20 surface of the sides of the cylindric air-chamber *f* as the ends of the said chamber, which is arranged on the ceiling of the stoke-hole, project into the water-separators *d* and extend nearly to the opposite side. Thus the 25 current of air is obliged again to change its direction before it gets into the air-chamber *f*, and consequently to impinge against the sides of this latter.

The air-chamber *f* is provided with a number of outlets *f'*, through which the cool moist air descends under the action of its weight 30 without causing any draft of air.

At *g* a filter is interposed into the suction-pipe *a'* of the pump *a*. This filter may 35 consist of a box *g'*, having sieve-partitions *g²*, between which porous material *g³*—such as loaf, (vegetable sponge,) for instance—is kept in place. The cover *g⁴* of the box *g'* is tightened on the top flange of the box by means 40 of cross-bars *g⁵* and screws *g⁶*.

The branch pipe *h* connects the delivery-pipe *a²* of the pump *a* with the outlet-pipe *d⁴* of the water-separator *d* and has a valve *h'* interposed into it. By adjusting the pressure 45 of the spring by which the said valve is weighted the quantity of water fed into the atomizers, and consequently the quantity of air sucked in by the jets of spray, may be controlled.

50 What I claim, and desire to secure by Letters Patent of the United States, is—

1. In an apparatus for ventilating and cooling the stoke-holes of steamships, the combination with the stoke-hole and its ventilation-shafts of water-atomizers arranged in the top 5 portions of the shafts and adapted to produce downwardly-directed jets of spray, means for supplying water under pressure to the said atomizers, chambers with inclined bottoms and baffle-plates connected with the bottom 10 ends of the said shafts and an air-chamber communicating with the said chambers, extending along the ceiling of the stoke-hole and having a plurality of outlets, substantially as described.

2. In an apparatus for ventilating and cooling the stoke-holes of steamships, the combination with the stoke-hole, its ventilation-shafts and the steam-boiler of water-atomizers arranged in the top portions of the shafts 15 and adapted to produce downwardly-directed jets of spray, a steam-pump adapted to be fed with steam from the boiler and having its delivery-pipe connected with the atomizers, chambers with inclined bottoms, baffle-plates and water-outlets into which chambers the shafts open, and an air-chamber, communicating with the aforesaid chambers, this air-chamber extending across the ceiling of the 20 stoke-hole and having a plurality of outlets, substantially as described.

3. In an apparatus for ventilating and cooling the stoke-holes of steamships, the combination with the stoke-hole, its ventilation-shafts and the steam-boiler of water-atomizers arranged in the top portions of the shafts 25 and adapted to produce downwardly-directed jets of spray, a steam-pump adapted to be fed with steam from the boiler and having its delivery-pipe connected with the atomizers, 30 chambers with inclined bottoms, baffle-plates and water-outlets, into which chambers the bottom ends of the shafts open, an air-chamber communicating with the aforesaid chambers, extending across the ceiling of the stoke-hole and having a plurality of outlets, and an automatic overflow-valve with adjustable load, the said valve tapping the delivery-pipe 35 of the pump, substantially as and for the purposes set forth.

In witness whereof I have signed this specification in presence of two witnesses.

MAX ROBITSCHEK.
